CURTAIN FABRIC OR SIMILAR ARTICLE

Barry Goodman, Forest Hills, N.Y., assignor to Universal Fabrics Co., New York, N.Y.

Filed Jan. 24, 1966, Ser. No. 757

Term of patent 14 years

(Cl. D92—1)

The figure of the drawing is a top plan view of a curtain fabric showing my new design.

The characteristic features of my design reside in the combination, on a curtain fabric, of spaced strings loosely draped in even rows on a fabric shirred in even rows, the strings being attached to the fabric at the shirring, all as shown.

I claim:

The ornamental design for a curtain fabric or similar article, as shown and described.
